BREADBOX OR THE LIKE

Maurice C. Lumley, Cincinnati, Ohio, assignor to
 The F. H. Lawson Company, Cincinnati, Ohio, a corporation of Ohio

Application June 4, 1949, Serial No. 3,051

Term of patent 14 years

(Cl. D44—5)

To all whom it may concern:

Be it known that I, Maurice C. Lumley, a citizen of the United States of America, residing at Cincinnati, in the county of Hamilton and State of Ohio, have invented a certain new, original, and ornamental Design for a Bread Box or the like, of which the following is the specification, reference being had to the accompanying drawings, form a part thereof.

Referring to the figures:

I claim:

The ornamental design for a bread box or the like, as shown.

MAURICE C. LUMLEY.
